UNITED STATES PATENT OFFICE.

JOHN E. TALLEY AND JOHN W. THOMPSON, OF PHILADELPHIA, PENNSYLVANIA.

DISPLAY APPARATUS.

Application filed May 12, 1920. Serial No. 380,713.

To all whom it may concern:

Be it known that we, JOHN E. TALLEY and JOHN WILMER THOMPSON, citizens of the United States, and residents of Philadelphia, Pennsylvania, have invented certain new and useful Improvements in Display Apparatus, of which the following is a specification.

Our invention relates to merchandise display structures, which may or may not be enclosed in suitable cabinets, and which are designed for use in retail stores, as well as sales-rooms and the like.

The object of our present invention is to improve certain details of construction in devices of this kind, and our present improvements involve more particularly special forms of rotatable, supporting means. In one instance these supporting means may be carried by a traveling carriage and be rotatable with respect to the carriage, and this may be adapted to suitable tracks which may be mounted in the top of a cabinet or disposed in the base of the same, as is desired. The carriage may be provided with a rod or standard which may be rotatable as a whole and carry suitable supports in the form of radially disposed arms, or the standard may be fixed and the radially disposed arms may be rotatable with respect thereto.

Additionally our improvements are adapted for use with movable display devices having a vertical standard which may be employed independently of an enclosing cabinet; such standard being provided with arms for the support of muffs or similar articles of merchandise. A further object of our invention is to provide various forms of telescopic arms adjustably carried by the standard whereby the amount of support afforded by the arms may be varied as desired.

The rotatable element of our improved display apparatus may be in the form of an enclosing tube mounted on a fixed rod so that the radially disposed supporting members carried by such tube may rotate therewith as a single unit, or rotatable members may be carried by ball-bearing collars supported at intervals throughout the length of the tube or the standard upon which the same are mounted, or the ball-bearing collars may carry the radially disposed supporting means.

These and other features of our inven-

tion, more fully described hereinafter, are indicated upon the accompanying drawings, of which:

Figure 1, is a sectional elevation of a merchandise display cabinet showing a traveling and rotatable supporting structure embodying our invention.

Fig. 2 is a similar sectional view illustrating another form of traveling and rotatable structure within the scope of our invention.

Fig. 3 is an enlarged sectional view illustrating details of the structure shown in Figure 1.

Figs. 4, 5 and 6 are sectional views illustrating details of the structure shown in Figure 2.

Fig. 7 shows a portable stand embodying features of our invention.

Fig. 8 is a sectional view, partly broken away, showing another form of portable stand within the scope of our invention, and

Figs. 9, 10 and 11 are views illustrating details of construction within the scope of our invention.

One important feature of our invention is the development of a goods display structure designed especially for the display of muffs or similar articles which may be conveniently suspended from radially projecting arms or spokes.

In Fig. 1 we have illustrated a goods display structure embodying our invention in which 1 may represent a suitable glass-walled cabinet of any usual type, having tracks 2 in the top of the same arranged to support a suitable carriage 3, from which may be hung a depending support 4. By preference this support is made up of an outer tubular member 5, having ballbearing connection with a central tube or rod 6, suspended from the carriage and held thereto by nuts 7; one ballbearing 8, being adjacent the carriage while the other ballbearing, indicated at 8^a may be carried by the lower end of the rod 6. The upper end of the rod 6 may be passed through a cross bar 9 of the carriage and secured by the nuts 7; being preferably held in fixed position by means of a set screw 9^a.

In the form of structure shown in Fig. 1 the outer tubular member 5 of the depending support is free to rotate on the ballbearings and it may carry, disposed preferably at definite intervals, collars 10 to which are attached in any suit- manner rods

11, forming the spokes or supporting arms for muffs or other articles of merchandise. In the present instance the rods are shown as being screwed into the collars. It will be understood, of course, that the outer ends of these arms may be provided with annular rails from which various forms of garments may be hung, and that they may serve as supporting means for shelves. If desired these arms may be telescopic and reference is made hereinafter to forms of telescopic arms suitable for the desired purpose.

In the form of structure illustrated in Fig. 2, a support 4^a is shown as mounted 15 on a carriage 3^a which may be adapted to tracks 2^a in the base of a display cabinet or casing. In this instance, a central shaft or rod 6^a may be fixed to the carriage in a suitable manner and is provided with a 20 conical bearing point 12 at its upper end adapted to engage a bearing block 13 carried in the head of the tubular member 5^a which encircles said shaft or rod 6^a. This provides a point bearing upon which the 25 tube and the arms supported thereby, may rotate. If desired, the lower end of the rod may be provided with a guide bearing of any suitable anti-friction type, illustrated at 14, in addition to the bearing 8^a.

30 In lieu of the arrangement shown in Fig. 4, wherein the fixed standard is provided with a bearing point to engage a bearing block carried by the upper end of the sleeve, these parts may be reversed, and the 35 vertical rod or standard, suitably supported and which may be in the form of a tube, may carry a bearing block 13^a suitably recessed for reception of a bearing point 12^a carried by the upper end of the sleeve; this 40 arrangement being clearly indicated in Fig. 8. While this view illustrates a portable structure it will be clearly understood that this detail may be applied to the type of structure illustrated in Fig. 2.

45 If desired, we may provide a structure of the type illustrated in Fig. 7, which is shown as portable, having a suitable base 15, with or without casters, to which a shaft or standard 6^b may be secured in any suitable manner. In this view we have shown 50 a built-up structure with various forms of goods-supporting units carried by the central shaft or standard. In building up this structure, a spacer sleeve 5^b may be first 55 applied to the shaft 6^b and the base may have a shoulder providing a seat to receive this sleeve. On top of the sleeve a suitable ball-bearing collar 8^b may be placed. This 60 may be of any usual type, having upper and lower cones with interposed balls, and an enclosing shell to loosely hold the cones together. If desired this shell may have a 65 depending flange 16 to fit inside the sleeve section 5^b and properly space the same from the central shaft; the cones of the bearing

having sufficient clearance from the latter to insure easy rotation.

Upon the ball-bearing collar 8^b, a sleeve section 5^c may be mounted, having radially-disposed arms or rods 11^a hinged thereto at 70 17 so as to be foldable against the central shaft when not in use. Upon the sleeve section 5^c, another ball-bearing collar 8^b may be mounted of the same type as the one disposed below the sleeve section 5^c, and upon 75 this may be mounted a collar 18 carrying radially-disposed arms or rods 11^b. In this instance these arms or rods are shown as telescopic and comprise stems 19 threaded into the collar, with slideable sleeves 20 for elongation within the limit of length of the respective parts. In order that the parts may be retained in position when elongated to the desired degree the stem may be provided with a lug 21 adapted to a slot 80 22 in the sleeve, and the latter may have notches 23 at intervals to receive such lug upon imparting slight rotative movement to the sleeve.

Upon this collar 18 a plain sleeve section 5^b may be placed and if desired a ball-bearing collar 8^c may be interposed between the same and the collar 18. This sleeve 5^b may be surmounted by a ball-bearing collar 8^b, and upon this may be mounted a sleeve section 5^d which may carry near its lower end sockets for the reception of radially-disposed supporting arms or rods 11^c, which may be of telescopic type. In this instance sleeves 20^a may be threaded into these sockets; and carry extensible stems 19^a. These parts may be held in their adjusted positions by providing the stems with lugs 21 adapted to slots 22 in the sleeves and the latter may be notched at 23 to regulate the 105 amount of extension and insure that the extended part will be retained in the adjusted position.

The top of this structure may have an ornamental cap 24 into which the upper 110 end of the central shaft or standard 6^b may be threaded and such cap may enclose the upper end of the sleeve section 5^d. It will be understood that supporting means may be built up of units of any of the types 115 illustrated in Fig. 7, and that in addition ball-bearing collars, which may carry any of the forms of arms shown in Fig. 7, may be employed in building up a suitable supporting structure by interposing the same 120 between sleeve sections of the spacer type illustrated at 5^b. It will also be understood that while we have shown these units as built upon a central shaft or standard carried by a portable base, they may be applied, 125 in any desired arrangement, to central standards of the type of structures illustrated in Figs. 1 and 2, without departing from our invention. A ball-bearing collar 8^d carrying supporting arms or rods is 130

shown in Fig. 9, and in Figs. 10 and 11, I have shown detached perspective views of the telescoping supporting arms which we may employ. An important feature of the built up structures is the fact that the size can be determined very readily to meet special conditions and with the sectional tubular units we may employ a sectional shaft or standard. As shown in Fig. 7, the several sections may be secured together by threaded nipples 24^a.

The collars 10 and 10^a shown in Figs. 1 and 2, may be adjustable with respect to the supporting rod or standard, and they are preferably held in their adjusted positions by means of set screws 29. If desired, the outer sleeve 5, shown in Figs. 1 and 3, may be provided with internal spacing shoulders, or projections 30, as indicated in Fig. 3.

It will be understood, of course, that the sectional structure shown in Fig. 7, may be inverted and suspended from a fixed point, or from a movable carriage such as illustrated in Fig. 1, and that as many sections as may be desired, of any of the forms illustrated in Fig. 7, may be employed.

It will be understood, of course, that any of the forms we have illustrated as being suspended may be reversed without changing the character or operative arrangement of the structure, and that any of the forms shown as being mounted upon a vertical

standard supported from the floor, may be inverted without changing the construction or altering the operative arrangements of the parts, and hung from a fixed point, or from a movable carriage, which latter may be mounted with reference to a track within or outside a cabinet or casing; all of which is deemed to be within the scope of our invention.

We claim:

The combination, in a goods display fixture, of an enclosing cabinet, a movable carriage disposed therein, a track-way for said carriage mounted within said cabinet, an elongated standard supported by said carriage and movable therewith, a ball-bearing collar loosely mounted at the lower end of said standard, a removable sleeve surrounding said standard and rotatable on said ball-bearing collar, a series of independent vertically movable collars adjustably secured to said rotatable sleeve, and a series of upwardly-inclined goods-supporting arms carried by each of said independent collars and radially disposed with respect thereto; said arms being made in sections telescopically arranged with respect to each other.

In witness whereof we have signed this specification.

JOHN E. TALLEY.
J. W. THOMPSON.
